UNITED STATES PATENT OFFICE.

CHARLES A. PARKER, OF HAUGAN, MONTANA, ASSIGNOR TO WESTERN AUTOMATIC COMPANY, OF SPOKANE, WASHINGTON.

TRAIN-CONTROL APPARATUS.

Application filed March 6, 1923. Serial No. 623,289.

To all whom it may concern:

Be it known that I, CHARLES A. PARKER, a citizen of the United States, residing at Haugan, in Mineral County and State of 5 Montana, have invented certain new and useful Improvements in Train-Control Apparatus, of which the following is a specification.

My present invention relates to improvements in train control apparatus for use on 10 steam railroads or electric railways employing automatic air brake systems for control of the train, whereby a moving train may be stopped by the automatic actuation of the air brake system to apply the brakes on a 15 train, or the train brought under the control of a train dispatcher or other person located at a distant point.

The train stop mechanism, which is automatically actuated, does not interfere with 20 the usual application of the brakes from the engineman's valve, but acts independently thereof to bring a train to a stop, in case the usual signals are disregarded, to prevent the train from proceeding into a block or 25 section ahead which is already occupied.

The apparatus of the invention is applicable for use on either single track or double track railroads, and utilizes both mechanically actuated and electrically actuated 30 mechanisms in combination with a trackside installation, and a stationary ramp rail and moving ramp shoe carried by the locomotive or tender, an electric motor, street car or other carrier equipped with the standard 35 form of air brake system.

Briefly stated the invention consists essentially in the combination with a standard air brake system for steam railroads or electric railways, of a control device including 40 an air valve mechanism interposed between the main reservoir of the air brake system and the engineer's valve on one side and the train line or main pipe on the other side, said valve being normally held open by 45 equalized air pressure for the usual passage of air from the engineer's valve to the train pipe. In connection with the equalizing device of the control member I utilize a train stopping device, which, when actuated 50 causes a reduction of the equalized pressure of air in the control device, resulting in cutting off the connection between the train line and the engineer's valve and simultaneously bringing about a reduction of pressure in 55 the train pipe, with consequent application

of the air brakes in usual manner. The train stop device is actuated through the instrumentality of a train carried ramp-shoe in co-action with a stationary ramp rail, and the ramp shoe is utilized, together with certain elements, for holding the train stop mechanism normally in inoperative position. Means are also provided whereby, after the brakes have been automatically set, the engineer may restore the train stop device to 60 its normal position and thereby permit automatic restoration of the required air pressure in the train pipe and release the brakes. The automatically operating train stop mechanism may be adjusted to gradually apply the brakes and thus bring the train to a 65 standstill without shock, but means, under control of the engineer, are provided for co-action with the automatic application of the air brakes whereby the reduction of air 70 pressure in the train pipe may be accelerated resulting in a more rapid application of the brakes and quicker stopping of the train. Other accessories insuring reliable control, 75 facile manipulation, strength of structures, 80 &c., and safety in traveling will be herein-after more specifically pointed out.

In the accompanying drawings I have illustrated one complete example of the physical embodiment of my invention in connection with a railroad employing a block system of control by electrically actuated semaphores, in which the parts involving my invention are combined and arranged according to one mode I have so far devised for the 85 practical application of the principles of my invention.

Figure 1 is a composite view showing the train stop and control mechanism in connection with the air brake system or the part 90 thereof carried by the engine, together with the ramp installation along the railway track, and a block signal of the semaphore type, the ramp mechanism being in position to actuate the train stop mechanism as the 95 train proceeds.

Figure 2 is an enlarged view of the train stop mechanism, carried by the engine.

Figure 3 is an enlarged, detail sectional view of the air control valve mechanism interposed in the air brake system between the engineer's valve and the train pipe. 105

In order that the relation of parts may readily be understood I have indicated a portion of the main air pipe or train line as 110

1 which is connected in usual manner for the purpose of applying the air brakes of a standard air brake system. The train line is supplied with air pressure from the main air reservoir B, which reservoir is supplied in usual manner from the pump equipment (not shown) with a pressure of say 130 pounds. C indicates the usual and standard form of engineer's valve for controlling air pressure between the main reservoir and train pipe, and is connected to the main reservoir or tank by means of a branch pipe or tank pipe D. The engineer's valve is connected to the train pipe A by two pipe sections 1 and 2, between which are interposed the air control device indicated as a whole by the numeral 3, and air supplied to the train pipe is normally at 70 lbs. pressure.

A cut out valve 4, of the double heading type is interposed in the pipe 2 between the air control device 3 and the train pipe. This valve may be manually closed after the train stop mechanism is actuated, and must be again opened, manually, by the engineer to permit restoration of the required air pressure for the automatic application of the brakes.

Referring especially to Figure 3 of the drawing the control valve is shown in detail as provided with a valve casing 5 with which the two pipe sections 1 and 2 communicate, and the valve casing has a partition 6 fashioned with a normally open valve seat 7. Through the operation of the train stop mechanism this valve seat is closed for automatic application of the brakes, by the valve head 8 which cuts off pressure, through the engineer's valve, to the train pipe A. An adjustable stop 9 in the form of a threaded bolt or screw, is provided in the valve casing 5 and aligned with the valve 8, to prevent, if desired, the complete closure of the valve seat.

The upwardly extending stem 10 of the valve is provided with a piston head 11, slideable in the cylinder 12 which is secured at its lower end to the valve casing 5, and at its upper end closed by a plug or cap 13. Above the piston and within the cylinder an expansion chamber 14 is thus provided and below the piston a reduction chamber 15 is formed, and under normal conditions the air pressure within these two chambers is equalized. A transverse partition 15' in the cylinder forms the lower wall of the reduction chamber and between this partition and the piston 11 a valve spring 16 is coiled, which, while the air pressure is equalized in chambers 14 and 15, holds the valve 8 away from its seat 7.

Air under pressure has free access to the expansion chamber at all times from the engineer's valve through a by-pass 17 extending through the valve casing and the cylinder wall to the chamber 14, and a branch

port 17' extends from this by-pass to the reduction chamber 15 below the piston, providing an equalized pressure above and below the piston when in normal position of Figure 3.

The spring retained valve 8, in normal position closes ports 18 in the lower head or end 19 of the cylinder, which head is threaded into the valve casing 5, and between this head 19 and the transverse partition 15' an outlet chamber 20 is provided. From the outlet chamber a short outlet pipe 21 extends and in this pipe a manually adjustable graduating valve 22 is interposed, which may be adjusted to permit outlet or discharge of air from the outlet chamber 20 to the atmosphere, but prevents entire expulsion of the air to zero point. Thus the graduating valve may be adjusted to a predetermined pressure, say 20 lbs. to prevent the too rapid discharge of air when the train is being stopped. By this adjustment the train may be stopped gradually when the brakes are automatically applied, to prevent danger of breakage of parts or undue wear on the equipment.

The valve casing 5 is equipped with an auxiliary plunger valve 23 to close a seat 24 in the valve-partition 6 between the two pipe sections 1 and 2, and this valve is held normally closed by its spring 25. Under normal conditions with the train line pressure equalized in the valve casing 5 this valve remains closed by its spring, but it is opened against tension of its spring, by air pressure in the pipe 2 under exhaust conditions.

Under normal conditions air at say 130 lbs. pressure from the tank B is supplied to the control valve 3 through the engineer's valve, which pressure is supplied through the open valve seat 7 between pipe sections 1 and 2 to the train line, A. When the train stop mechanism is actuated as will be described the air pressure in chamber 15 is reduced by passage through a reduction pipe 26 which communicates with this chamber. Because of this reduction in pressure in chamber 15, the higher pressure in chamber 14 forces down the piston, valve 8 and its stem, against tension of the valve spring. The valve is forced to its seat 7 closing communication between the pipe sections 1 and 2 and cutting off pressure through the valve 3 by way of the engineer's valve. The movement of the piston closes port 17', and the movement of the valve opens ports 18 permitting air to flow from pipe 2 through these ports into the discharge chamber 20, and thence to the atmosphere through the discharge pipe 21 and its graduating valve 22. This flow of air causes a reduction in the train line pressure and consequently an application of the air brakes throughout the brake system in usual manner. While the brakes are being applied the valve 8 is held

to its seat 7 by high pressure of air above the piston 11 in expansion chamber 14, and of course, before the train can proceed, the valve 8 must be restored to its normal position of Figure 3. The cut out valve 4 in pipe 2 is closed by the engineer to prevent escape of the reduced air pressure from the train line, and then by manipulation of the engineer's valve C all air is exhausted from 10 between the cut-out valve 4 and the engineer's valve C. The valve spring 16 is now free to elevate the piston 11 thus withdrawing the valve 8 from its seat 7 to re-establish the train line pressure and ports 18 are closed 15 by the valve when restored to its normal position. The cut-out valve 4 is opened by the engineer, and the valve C is manipulated to restore the normal pressure throughout the entire line.

20 Should an emergency require a quicker stop of the train than is being accomplished by the action of the control valve as here described, the engineer may assist in the application of the brakes by manipulating the 25 valve C to exhaust air therethrough from the pipe 1 thus withdrawing pressure from beneath the closed valve 23. Air pressure from pipe 2 is now relieved through the open auxiliary-valve seat 24, in addition to the exhaust by way of the discharge pipe 21, thus 30 more rapidly reducing the pressure in the train line with consequent accelerated application of the brakes. When the train line pressure is again restored, the valve spring 35 25 closes its valve 23 to normal position.

In order that the above described operation of the control valve 3 may be accomplished I utilize a train stop mechanism in connection with the reduction pipe 26, which 40 is provided with two normally closed air valves 27 and 28 which are enclosed, with other parts of the stop mechanism in a housing 29 that may be located in the engine cab, or at other suitable place.

45 The valve 27 is held normally closed through the instrumentality of a ramp actuated mechanism carried by the train, or the engine and adapted to co-operate with a ramp rail 30 at the track side. A resilient, 50 flexible ramp arm 31 is carried, as by a truck 32, and the pivoted ramp shoe 33 on the arm has connected thereto a cable 34, under tension and held in that condition by 55 the resilient ramp arm, except when the ramp shoe is riding up the tread of the ramp rail in the manner indicated in Figure 1.

By means of an eye-bolt 35 the cable is 60 connected to a bell crank lever 36, pivoted at 37 to a stationary support in the housing 29, and a spring 38 is coiled about the bolt and interposed between adjusting nut 39 on the bolt and one arm of the bell crank lever. Manipulation of the adjusting nut on the 65 bolt tightens the cable, with the result that

the resilient and flexible ramp arm is flexed upwardly and held under tension.

The bell crank lever is thus pressed against the valve stem 40 of the spring pressed valve 27, to hold said valve normally closed. When the ramp shoe slides over the ramp rail, the cable is slackened, the bell crank lever is released, and air pressure in pipe 26 forces the valve 27 open for passage therethrough of air under pressure 70 from the reduction chamber 15. The bell crank lever is swung on its pivot 37, swinging out the long latch arm 41 to dotted position in Figure 2. This arm in normal position supports an armature 42 of an electro-magnet 43, and the armature co-acts mechanically as a latch in connection with the latch arm 41 of the bell crank lever. Assuming the magnet 43 is deenergized, and the armature latch is resting on the latch arm 41, 80 when the latter swings to the left on its pivot 37 in Figure 2, this armature-latch drops into engagement with the latch arm and holds the bell crank lever in its dotted position, thus permitting the valve 27 to remain open for the passage therethrough of air under pressure. Air passing through pipe 26, also automatically opens valve 28 and passes therethrough to the atmosphere. Due to this passage of air and escape of the 95 air from pipe 26, the brakes are applied as heretofore described.

If a train is approaching a clear signal, as 44, in Figure 1, the ramp rail 30 (being energized) is encountered by the ramp shoe 100 and direct electrical contact is made between these parts. Electrical current now passes through the conductor wire 45 from the ramp arm 31 to the magnet 43, and thence to ground at 46 in Figure 1. The magnet is thus energized to hold the latch 42 out of position for engagement with the latch arm 41, until the ramp shoe has moved entirely over and off of the ramp rail. As the shoe 105 passes down the inclined tread of the ramp rail, the resilient ramp arm (which has previously been elevated as it rode up the ramp rail) pulls the bell crank lever to normal position before the electric circuit is broken, and valve 27 is also closed before 110 the brake operating mechanism can be operated.

115 Valve 28 also is held normally closed, to prevent application of the brakes, when the ramp shoe is passing over an energized ramp rail, and a second armature 47 is influenced by the magnet 43 to preserve this condition and prevent application of the brakes. This valve 28 has a stem 48 pivotally connected to a suspending arm 49 that is pivoted at 120 50 in the casing 29, and a spring 51 tends to hold said arm in normal position with the valve 28 closed, in combination with the armature 47.

125 The suspending arm is pivotally con- 130

nected to the armature 47 by a loose link 52. After the ramp shoe passes over its ramp rail, the armature 47 is released, and the pressure in the small pipe 26 is open to the atmosphere. Spring 51 is used to restore the valve 28 to normal position.

While it will be apparent that during the interim the ramp shoe is passing over the ramp rail, (while the latter is energized) or 10 should the train stop with its shoe resting in contact on the ramp rail, a slight exhaust of air may take place through valve 27, it will be understood that the valve 28, which remains closed during this time, will function to prevent exhaust of air to the atmosphere, and thus prevent application of the brakes under these conditions.

When the semaphore occupies the dotted position which indicates a signal to stop, 20 the circuit of the control magnet 43 remains open, and the de-energized magnet permits the operation of the stop mechanism.

After the brakes have thus been automatically applied and the train brought to a stop as heretofore described, it is necessary, before the train can proceed, to reset the stop mechanism to a normal or running position. For this purpose a branch pipe 53 is connected to the train pipe A, and provided with a manually operated valve 54 which may be opened by the engineer or fireman to permit passage therethrough of part of the remaining air pressure in the train pipe. 30 Air under pressure then passes through said valve and pipe, and impinges against a plunger cap 55, which is operatively connected to actuate a three arm lever pivoted at 56 in the housing 29. An arm 57 of this lever is operatively arranged and adapted to swing upwardly and engage the latch 42, lift said latch and free it from the latch arm 41 of the bell crank lever 36. When thus released said lever 36 is permitted to return from its locked position (shown in dotted lines) to normal position (in full lines) after which movement the arm 57 is forced back to its normal position in Figure 2 by the action of this interlocking of parts.

50 In the meantime the spring 51 will function to replace the armature 47 in its normal position and raise the valve stem 48 to close its valve 28, thus shutting off passage of air to the atmosphere.

55 Should the signal system be out of order, and the engineer be given orders to disregard the signal 44 and proceed into the next block, he may prevent action of the stop mechanism and automatic application of the brakes at each block or signal, by opening a valve 54 heretofore referred to. Air pressure in pipe 53 will then actuate lever 57, which will lift armature 42 and hold it uplifted, thus permitting the bell crank lever 36 to operate without locking the stop

mechanism in operative position. This action will also permit the arm 58 to operate against the suspending arm 49 to prevent opening of the valve 28, thus permitting a train to pass a ramp rail without causing the 70 brakes to be applied.

The block signal or semaphore 44 is electrically operated in usual manner, and is dropped from clear position shown in full lines to stop position in dotted lines as indicated in Figure 1, after a train has passed the signal, to prevent a following train from entering the occupied block.

The electric circuits are normally open, i. e., the ramp circuit indicated in Figure 1 80 and traced through ramp rail 30, wire 58', switch 59, battery 60, signal control relay 61, and wire 62 to the insulated track rail 63, is closed when the semaphore is in clear position for proceed. However, when the semaphore is set in stop position, and the stop mechanism on the engine is to be actuated, as indicated in dotted lines, the ramp circuit is open and the ramp 30 is de-energized. The magnetic control circuit is also open 90 when the ramp 30 is de-energized, and therefore the de-energized magnet 43 cannot exercise influence over its two armatures, and will permit the armature latch 42 to fall by gravity and lock the bell crank lever 36 in position to permit passage of air through pipe 26 and valves 27 and 28 to cause the application of the brakes and bring a train to a standstill.

The flexible and resilient ramp arm 31 is 100 held under tension, and it in turn holds the train control and stop mechanism taut and under tension against movement, while the train is running. If desired, a yoke 64 may be attached to the truck 32, as in Figure 1 105 to restrict movement of the resilient arm 31, said yoke enclosing the arm near its free end to limit its movement, but permit the required freedom of movement of the ramp arm.

Having thus fully described my invention, what I claim as new and desire to secure by Letters Patent is:—

1. An air control device comprising a casing having a valve seat, a cylinder and a 115 piston therein forming a closed expansion chamber and a reduction chamber and means for providing an equalized pressure in said chambers, a valve connected with the piston and held out of contact with said seat by 120 equalized air pressure in said chambers, train control mechanism adapted to reduce pressure in said reduction chamber, an exhaust chamber in the casing, an exhaust pipe connected thereto, and exhaust ports 125 adapted to establish communication between said casing and exhaust chamber when said valve seat is open.

2. The combination with a valve casing having a normally open seat and a train pipe 130

connection, of a cylinder having a head in said casing, an exhaust chamber and ports between said casing and chamber, a valve and a piston connected thereto forming a closed expansion chamber and a reduction chamber and communicating with the train pipe connection to normally receive equalized air pressure, and means for reducing pressure in the reduction chamber.

10 3. The combination with a valve casing having a normally open seat, of a cylinder having a head in said casing, an exhaust

chamber and ports between said casing and chamber, a valve normally closing said ports, a piston connected with the valve forming a closed expansion chamber and a reduction chamber having normally equalized pressure and a spring engaging said piston to hold the valve normally closed, and means for reducing pressure in the reduction chamber whereby the piston is pressure actuated to close said valve.

In testimony whereof I affix my signature.

CHARLES A. PARKER.
